UNITED STATES PATENT OFFICE.

GLENN W. WATSON, OF DETROIT, MICHIGAN, ASSIGNOR TO DIAMOND POWER SPECIALTY COMPANY, OF DETROIT, MICHIGAN, A CORPORATION OF MICHIGAN.

BLOWER FOR BOILERS.

1,243,464.

Specification of Letters Patent.

Patented Oct. 16, 1917.

Application filed December 18, 1915. Serial No. 67,518.

To all whom it may concern:

Be it known that I, GLENN W. WATSON, a citizen of the United States of America, residing at Detroit, in the county of Wayne 5 and State of Michigan, have invented certain new and useful Improvements in Blowers for Boilers, of which the following is a specification, reference being had therein to the accompanying drawings.

10 It is the object of the invention to obtain a simplified construction of blower for water tube boilers, in which the blower jets are so arranged as to sweep the spaces between adjacent rows of tubes, and when not 15 in use to be protected from the furnace heat. Heretofore blowers have been devised in which a series of nozzles projecting through apertures in the furnace wall have been individually rotatively adjustable to sweep the 20 spaces between rows of tubes. Such constructions necessitate a series of operating devices for adjusting the different nozzles, each of which passes through the furnace wall and is subjected at its inner end to the 25 furnace heat. The nozzles are, however, simultaneously operated by a common actuating mechanism outside of the furnace wall. To simplify the construction and also the work of installation I have devised a blower 30 in which there is a single steam supply conduit and a single nozzle-operating device passing through the furnace wall, together with a laterally-extending swiveled arm rotatively actuated by said operating device 35 and having a series of jet nozzles projecting therefrom. I have further made provision for protecting the blower when not in use, comprising a recess in the inner face of the furnace wall into which the laterally-projecting arm may be withdrawn.

In the drawings:

Figure 1 is a horizontal section through a portion of the furnace wall showing my improved construction of cleaner applied thereto;

Fig. 2 is a vertical section therethrough;

Fig. 3 is a sectional plan view showing a slightly modified construction; and

Fig. 4 is a front elevation of a portion of 50 the construction shown in Fig. 3.

In detail, A is the wall of the furnace and B B' etc. a series of rows of tubes of a water tube boiler which are arranged within the furnace chamber. C is the steam supply 55 conduit for the blower which is connected

to a hollow head or cylinder D projecting in to an aperture through the furnace wall and suitably anchored therein as by the collars E. F is an extension pipe telescopically engaging the hollow head or cylinder D and 60 extending through the furnace wall. This extension pipe is provided with a rearwardly-extending guide rod or shank G passing out through the cylinder D and having sleeved thereon a spring H engaging 65 a collar or head I upon the shank to normally retract the extension F. J is a laterally-extending hollow arm which is swiveled in a suitable bearing K at the outer 70 end of the extension pipe F so as to be rotatively adjustable. A suitable operating mechanism for rotating the arm J is provided which as shown comprises a rock-arm L on the arm J connected by a link M to a rod N, which passes outward adjacent to 75 the pipe F and is mounted in suitable bearings thereon. The outer end of the rod N is provided with a hand-wheel O or other means for rotating the same and a threaded portion of said rod engaging a threaded 80 bearing in the collar I serves to cause a longitudinal movement of the rod upon rotation thereof. Any other suitable actuating mechanism may be employed by which the arm J may be rotated through a limited 85 angle by a single actuating means operable from outside of the furnace wall. The arm J is provided with a series of jet nozzles P which as shown are arranged in alinement with the spaces Q between adjacent rows of 90 tubes B B' etc., and thus each jet during the rotative adjustment of the arm J will sweep the space between adjacent rows of tubes.

The longitudinal adjustment of the extension tube F is sufficient to move the arm J from a position where it is clear of the furnace wall adjacent to the tubes to a position where it is retracted into the recess R on the inner face of the wall. The latter position 100 is the normal one when the apparatus is not in use, and the tension of the spring H is sufficient to adjust the parts into this position whenever the steam pressure is relieved.

In use, to clean the boiler tubes the admission of steam through the conduit C to the cylinder D will cause the outward projection of the extension pipe F, carrying with it the laterally-extending arm J. At the same time steam will be discharged from 105 110

each of the nozzles P into the registering space between adjacent rows of tubes, and the operator by manipulating the hand-wheel O can rotate the arm J as a unit 5 sweeping the jets through the desired angle. As soon as the steam pressure is relieved the spring H will retract the tube F, carrying with it the arm J and withdrawing the latter into the recess R where it is protected 10 from the intense furnace heat.

The construction as described has a decided advantage over constructions employing a series of nozzles each having its individual actuating device,—first, because the 15 construction is simplified and cheapened, and second because it requires only a single perforation in the furnace wall.

In Figs. 3 and 4 I have shown a modified construction which facilitates the forming 20 of the recess into which the blower is withdrawn when not in use. With this construction in place of forming the recess in the brick work I have provided a hollow metallic casing S which is placed in the furnace 25 wall in the space occupied by a single course of brick. This casing has an enlarged central portion T of sufficient size to receive the member D, while the main portion of the casing is of sufficient length and depth 30 to receive the rotary blower arm J. Thus as shown in dotted lines in Fig. 3 the blower

is completely withdrawn in the chamber provided by this casing, while in full lines in the same figure the blower is shown extended to be outside of the casing and in 35 proximity to the water tubes to be cleaned.

What I claim as my invention is:—

A blower for water tube boilers, comprising a conduit longitudinally adjustable through a furnace wall, a laterally-extending hollow arm swiveled in the inner end of said conduit and provided with a series of jet apertures, a rod extending through said wall parallel and adjacent to said conduit, a connection between the inner end of said rod 45 and said hollow arm for rotating the latter upon longitudinal displacement of the former, a collar having threaded engagement with the outer end of said rod, a member extending from said adjustable conduit outwardly in proximity to said rod and carrying said collar, a spring acting outwardly upon said collar, and means for normally 50 rotating said rod to longitudinally adjust the same through its engagement with said 55 collar.

In testimony whereof I affix my signature in presence of two witnesses.

GLENN W. WATSON.
